UNITED STATES PATENT OFFICE.

FREDERICK W. PARSONS, OF CLEVELAND, OHIO.

THERMAL CONTROL CABLE.

Application filed May 8, 1922. Serial No. 559,429.

To all whom it may concern:

Be it known that I, FREDERICK W. PARSONS, a citizen of the United States, residing at Cleveland, in the county of Cuyahoga and State of Ohio, have invented certain new and useful Improvements in a Thermal Control Cable, of which the following is a specification.

My invention relates to a thermal control cable and my general object is to provide a fusible wire or cable adapted to be stretched along the walls and ceilings and underneath and over and through any part or place in a single room or any number of rooms in a building where the fire hazards or risks make it desirable or necessary to effect immediate operation of some safety device, signal or alarm within or without such building upon the breaking out of a fire in any protected spot or place in the room or building. More specifically, my object is to provide a cable of indeterminate length made in sections united together with fusible couplings or fusible solder, whereby when any one of these fusible places of union soften or melt the cable will part immediately under a slight strain or tension.

In the annexed drawing, Fig. 1 is a sectional view of a building, showing a fire door having a tripping device connected with and under the control of a fusible cable constructed according to my invention and stretched in running engagement with sheaves or pulleys mounted upon the ceiling and walls of two rooms of the building. Fig. 2 is an enlarged view of a relatively short length of cable but embodying several sections and fusible unions, and Fig. 3 is a larger sectional view longitudinally through one of the solder unions. Fig. 4 is across section on line 4—4 of Fig. 3.

In many industrial establishments the fire hazards are so great that every precaution is taken to prevent fires and the spread of any fire which may start or occur. Thus it is a common expedient to employ overhead sprinkling systems, electric signaling systems and alarms, fire doors and windows, etc., which operate automatically to perform their particular function when the fire occurs within the protected zone. The present invention, comprising a sectional fusible cable 2, is particularly designed for use in connection with such systems, alarms, fire doors and windows, and is exemplified herein in connection with a

gravity sliding fire door 3 operating to close a doorway 4 in one of the walls of the building B. A pivoted tripping lever 5 having a catch 6 at one end is adapted to engage an arm 7 fixed to door 3 and to hold the door open as long as the counterweighted arm 8 of the lever is upheld. To that end I have conceived the idea of using a relatively long wire cable 2 made of short sections 9 united together at their meeting ends by bonds 10 of fusible solder. The number of sections and fusible bonds used are dependent upon the length of the cable required to reach any remote or distant point from the fire door whether located in the same room or in other rooms near or adjoining. The fusible bonds 10 are preferably placed at close intervals, say every six feet, to provide a multiple of parting places in a single cable stretched taut along the walls, or ceiling of the building and passing in running engagement with pulleys or sheaves 11 mounted wherever deviation in direction of the cable or a suspensory support therefor is required.

A single cable may extend either on straight or circuitous lines throughout a room and to other rooms adjoining, and also pass underneath work benches, or above or parallel with storage bins containing inflammable goods or materials, and each fusible bond in this extended chain of links establishes an independent protective fire zone. A fire starting in any one of these zones will have an immediate effect on the cable and the tripping lever or other device with which the cable is connected.

As shown in Fig. 1, cable 2 is held taut and under constant tension by a weight 12 which is heavier than the counter weight 11 on the tripping lever. In this way the door is held open as long as the cable does not part, but if any one of the numerous fusible bonds disunite due to fire or heat radiated in its immediate area the cable will part and the counterweight 11 will trip the door and permit it to close by gravity long before the fire could reach the door and spread to the other room.

As shown in Fig. 3, the flexible cable sections consist of twisted wire strands, but the ends or terminals of each cable section are opened and spread apart to provide straight parallel strands 14 which may be interlaid between the corresponding straight end strands 14 of the next succeeding sec-

tion of the cable. These interlaid meeting ends are embedded within a tapering round body 15 of solder possessing the property of fusing or melting at approximately 110° to 360° F. although the fusible composition may vary considerably and have different fusing properties dependent upon the place of use of the cable. The straight strands as interlaid and united together with the fusible solder permit the cable sections to part very readily under a tensile strain when exposed to heat at the desired temperatures, but nevertheless the sections are strongly bonded and united together under all other conditions.

A sectional cable embodying a multiplicity of fusible joints, bonds or unions as described may be made in any length and extend many hundred feet through a factory or other building and function effectively throughout its full length. It is also an article of manufacture and sale in itself, being adaptable to and useful as a control element in many different kinds of fire protective systems and appliances. Therefore, I do not claim in this application the particular combination of appliances shown and described herein, but claim instead the control element itself in its preferred form and in and to any and all modifications thereof to which I may be entitled.

What I claim is:

1. As an article of manufacture and sale, a thermal control cable for fire protection uses, comprising a series of cable sections made of twisted wire strands, the strands being separably interlaid at their meeting ends and bonded together solely with relatively small bodies of low fusing solder, 35 said bodies being of relatively small di-

ameter and without sharp or abrupt projections.

2. As an article of manufacture and sale, a flexible thermal control cable made in sections of twisted wire strands, the strands being separably interlaid at their meeting ends and bonded together solely with relatively small cylindrical bodies of low fusing solder, said cable and its fusible bodies having a substantially smooth surface throughout its length to permit the cable to slide freely without obstruction in use.

3. As an article of manufacture and sale, a thermal control cable consisting of a multiplicity of relatively short sections of 55 twisted wire strands, the respective meeting extremities of all of said sections having the strands untwisted and spread apart and interlaid on substantially parallel lines and inter-digitally united together solely with 60 low fusing solder, the said cable and its fusible unions of solder being of relatively small diameter and without sharp or abrupt projections throughout its length.

4. As an article of manufacture and sale, 65 a comparatively long and slender tension wire cable for fire protection uses, made of a relatively large number of strands separably interlaid on substantially parallel 70 lines and bonded together solely with relatively small cylindrical bodies of low-fusing solder with smooth rounded ends, the cable as a whole having a substantially continuous smooth surface of relatively small diameter throughout its length.

In testimony whereof I affix my signature in presence of a witness.

FREDERICK W. PARSONS.

Witness:

GEO. E. KRICKER.
